Charles L. Wright
ATTORNEY

UNITED STATES PATENT OFFICE.

ALFONSO HERING, OF BROOKLYN, NEW YORK.

REVERSIBLE TYPEWRITER-TYPE.

1,401,471.

Specification of Letters Patent. Patented Dec. 27, 1921.

Application filed March 3, 1921. Serial No. 449,318.

To all whom it may concern:

Be it known that I, ALFONSO HERING, a citizen of Chile, S. A., and a resident of Brooklyn, in the county of Kings and State 5 of New York, have invented certain new and useful Improvements in Reversible Typewriter-Type, of which the following is a specification.

The principal purpose of this invention is 10 to provide novel and practical means for enlarging the range and scope of characters on any type bar machine without increasing the number of key levers or changing the machine in any manner other than substituting 15 improved type bars for certain of the common style and the use of special type reversibly and removably engaged thereto.

Another object is to provide a form of type, and typebar head used in connection 20 therewith, that conform to the standard type of the machine in proportions, dimensions, weight and all essential characteristics, but which are so arranged as to double the character capacity of the machine.

25 A further object is in the provision of such devices in forms which present no difficulties in manufacture, assemblage or operation, the type and bar being essentially simple and cheap, strong and durable, and 30 easily reversed when desired by the fingers.

These objects are attained by the novel construction, combination and arrangement 35 of parts hereinafter described and shown in the accompanying drawings, forming a material part of this disclosure, and in which:—

Figure 1 is a front elevational view of a type made in accordance with the invention, as applied to a conventional form of type bar.

40 Fig. 2 is a side elevational view thereof.

Fig. 3 is a perspective view of the same showing the type carrying element in a partially reversed position.

Fig. 4 is a perspective view of the type 45 block in detail looking from the under side.

Fig. 5 is a perspective view of the type back retaining means in detail.

Fig. 6 is a side elevational view of the type 50 block as applied to an Underwood type bar, drawn to a reduced scale.

Stated in general terms, the invention consists in forming an open or hollow head on any style of type bar, the head conforming in thickness with the width of the type block 55 and drilling the head diagonally at approximately forty-five degrees from its face.

The type block, which is of integral construction, presents two branches disposed at right angles, one of the branches bearing on its outer face the number of characters carried by the ordinary type of the machine; as for instance in a single shift typewriter, each type block carries two characters, as the upper case or capital and lower case or small letter, as the "N" and "n" shown. 60

The other branch carries in a similar manner any two other characters, as the English pound sterling and paragraph marks, although obviously any preferred characters may be used. 65

Extending centrally between and from the junction of the branches is a cylindrical stem suited to engage the drilled hole in the type bar head and provided near its end with an annular recess in which is received the forked 70 end of a curved flat spring disposed within the opening in the head and having its opposite end shaped to partially encircle the stem, bearing against the inner wall of the opening. 75

Thus the spring tends to draw the branches of the type block snugly against the upper and front faces of the type bar head, but permits the stem to be withdrawn in reversing the relative position of the type block 80 branches and it can be bodily removed in dismounting the block. 85

Referring now more particularly to the drawings in detail, the numeral 10 designates the shank of a conventional type bar, 90 such for instance as is used in the Remington machines, provided with a guide spur 11 and having a thickened head 12 extending to the front.

In Fig. 6, the Underwood type bar 10' is 95 formed with a like head and it is to be noted that these heads, when the type block is in position, extend outward precisely the same distance as those of standard construction.

The lower, front corner 14 of the head is 100 square while the upper front corner 15 is curved, presenting two flat faces 16 and 17 at a right angle to each other, the central portion of the head being removed, forming a diagonally disposed, oblong opening 18, reducing weight and providing space for purposes farther on apparent. 105

A hole 19 is drilled through the curved upper corner 15 midway in the thickness of the head, the hole bisecting the opening 18 110 and extending, as at 19', into, but not through, the lower rear corner of the head

near its junction with the bar, the axis of the hole being at forty-five degrees from the seating surfaces 16 and 17.

The type block consists of two elongated rectangular members 20 and 21, alike in all their dimensions and bearing on their exposed outer faces type characters as indicated.

Thus for machines having a single character on each key lever, one character would appear on each face; if a single shift machine is used, two characters, and for a double shift machine, three characters on each face are required.

15 It is to be understood that in all cases the type characters agree with those used in the machine on one of the faces, while on the other face additional characters, marks, fractions, symbols, etc., are displayed, 20 thereby doubling the capacity of the machine and adapting it for foreign language and like purposes in a convenient manner.

A solid round stem 24 is formed with or united at the junction of the branches, the 25 stem being so located as to fit the drilled holes 19 and 19' and when entered to seat the rear surfaces of the branches neatly upon the faces 16 and 17 of the type bar head, constituting to all intents and purposes a 30 solid type.

In order to maintain the stem in position an annular groove 25 is formed near its outer end, within the space 18 and fitting the groove is the fork 26 of a curved flat spring 27, the same being suited to be entirely received within the space and having a concave opposite end 28 engaging the body of the stem 24, the outer surface of the spring abutting the wall of the opening in 40 such manner as to press the stem inwardly forcing the branches against their seats.

In operation, the ordinary character on the type branch are used in the customary manner by striking their corresponding key 45 lever; when the additional characters are required, the type bar is raised into position to grasp the type block by the fingers, and reversed in position, as indicated in Fig. 3, whereupon by releasing the block, it is 50 drawn by the spring into operative position with the additional characters ready for use.

Thus it will be seen that no changes are made in the machine except substituting the improved type bars for those originally furnished and that a practical device capable of fulfilling the several objects has been disclosed.

While certain preferred embodiments of this device have been shown and described, 60 it will be understood that changes in the

form, arrangements, proportions, sizes and details thereof may be made without departing from the scope of the invention as defined in the appended claims.

Having thus described my invention, what I desire to secure by Letters Patent and claim, is:—

1. A type-bar having a perforate head containing a diagonal bore extending from its upper front corner, a branched type block 70 having a stem revolvably fitting the diagonal bore, and means in said head engaging said stem, said means resiliently drawing the type block into intimate contact with the front face of said head. 75

2. A type-bar having a perforate head containing a diagonal bore extending from its upper front corner, a branched type block having a stem revolvably fitting the diagonal bore, a flat semi-elliptical spring having 80 forked ends disposed in said head, one of said forked ends engaging a recess in said stem, the other end partially encircling the stem and abutting against the interior of the head. 85

3. A type-bar having an essentially rectangular head corresponding in thickness with the type, said head containing a transverse opening and a bore bisecting the angle of its upper and front faces, an angular 90 type block adapted to seat against said faces, the outer surfaces of said block each bearing one or more type characters, a stem formed with said block at the junction of its angular elements, said stem being suited to the mentioned bore, and means disposed in the type head opening for retaining said stem and permitting its rotation. 95

4. A type block formed of two sections disposed at right angles, each section carrying one or more type characters, a stem extending from the junction of said sections, said stem having a recess, a type bar head suited to engage said sections on its upper and front faces, said head being drilled to 100 receive said stem, and means in said head engaging the mentioned recess whereby the block and head are maintained in operative relation. 105

5. A type block formed of two sections 110 disposed at right angles, each section carrying one or more type characters, a stem extending from the junction of said sections, a type-bar head on which said sections are revolvably mounted, and means in said head 115 for resiliently retaining said stem therewithin.

In testimony whereof I have signed my name to this specification.

ALFONSO HERING.
